(57) **CLAIM**

The ornamental design for a multi-piece cutting board, as shown and described.

DESCRIPTION

FIG. 1 is an exploded perspective view from the bottom-side of our multi-piece cutting board with the pieces separated; FIG. 2 is a perspective view from the top-side of the multi-piece cutting board with the pieces separated as shown in FIG. 1;

FIG. 3 is top plan view of the multi-piece cutting board shown in FIG. 1 and FIG. 2 with the pieces assembled;

FIG. 4 is bottom plan view of the multi- piece cutting board shown in FIG. 1 and FIG. 2 with the pieces assembled;

FIG. 5 is an exploded side view of the multi- piece cutting board shown in FIG. 1 and FIG. 2 with the pieces separated;

FIG. 6 is an exploded end view of the multi- piece cutting board shown in FIG. 1 and FIG. 2 with the pieces separated;

FIG. 7 is a side view of the multi- piece cutting board shown in FIG. 1 and FIG. 2 with the pieces assembled;

FIG. 8 is an end view of the multi- piece cutting board shown in FIG. 1 and FIG. 2 with the pieces assembled;

FIG. 9 is a cross-section view of the multi-piece cutting board shown in FIG. 1 and FIG. 2 taken at line 9 of FIG. 3; and,

FIG. 10 is a cross-section view of the multi-piece cutting board shown in FIG. 1 and FIG. 2 taken at line 10 of FIG. 3. The broken lines shown throughout the drawings form no part of the claimed design.
